TRAFFIC LOCKING CIRCUIT

Clifford D. Ihrig, Edgewood, Pa., assignor to The Union Switch and Signal Company, Swissvale, Pa., a corporation of Pennsylvania

Application March 21, 1942, Serial No. 435,745

5 Claims. (Cl. 246—26)

My invention relates to railway traffic controlling apparatus, and particularly to traffic locking apparatus.

When traffic is to be operated in either direction over a railway track extending between two spaced locations, traffic locking apparatus may be provided which includes a traffic locking circuit controlled jointly by two operators, one at each end of the stretch of railway track. Such traffic locking circuit is arranged to prevent the manipulation of traffic governing signal levers or units for changing the direction of traffic on the stretch of track between such two spaced locations while the stretch is occupied, or while a signal is displayed for a train to proceed into such stretch.

It is an object of this invention to provide improved traffic locking apparatus which requires less equipment than the means heretofore known.

Another object of the invention is to provide improved traffic locking apparatus which is arranged so that the traffic locking relays function also as directional stick relays to thereby eliminate the need for separate directional stick relays.

A further object of the invention is to provide improved apparatus of the type described.

In practicing my invention I provide a polarized traffic locking relay at each end of the protected track stretch and provide means for energizing these relays in series with energy of one polarity or the other when the protected stretch is vacant. These relays govern the signals controlling entrance of trains into the protected stretch, while the equipment is arranged so that the operator at either end of the protected stretch can cause the traffic locking relays to be energized with energy of the polarity effective to permit clearing of the signals governing entrance of trains into that end of the protected stretch only if the signals governing entrance of trains into the other end of the protected stretch are displaying their stop indications. Furthermore, the control of the traffic locking relays is arranged so that after these relays have been energized to permit clearing of the signals at one end of the protected stretch, and a train thereafter enters this stretch, the circuit for energizing the traffic locking relays in series is interrupted to prevent clearing of the signals at the other end of the protected stretch, while a stick circuit is established to energize the traffic locking relay at the end of the stretch at which the train entered so that this relay maintains the circuits of the associated signals and thus permits these signals to be conditioned to authorize a second or following train to enter the protected track stretch.

I shall describe one form of traffic locking circuit embodying my invention, and shall then point out the novel features thereof in claims.

In the drawing the single figure is a diagram 5 of a stretch of railroad equipped with signaling apparatus embodying my invention.

Referring to the drawing, there is shown therein a stretch of track having track rails 1 and 2 over which traffic may move in either direction. Adjacent the left-hand or west end of the single track stretch is a passing siding or branch track 3PS which is connected by switch 3W with the single track stretch, and adjacent the right-hand or east end of the single track stretch is a passing siding or branch track 5PS which is connected by a switch 5W with the single track stretch. The switches 3W and 5W and the signals associated therewith may form parts of interlocking installations at their respective locations.

20 Although the equipment is illustrated in connection with a single track stretch joining two passing sidings or branch tracks, the system is not limited to use in situations of this kind, and may be employed wherever traffic may move in either direction between two points, but only in 25 one direction at one time.

The track rails 1 and 2 are divided by insulated joints 3 into track sections for signaling purposes. As shown there is a section 3T which 30 includes the switch 3W, and a section 5T which includes the switch 5W, while the single track stretch between sections 3T and 5T forms a track section 4T. Each track section is provided with track circuit apparatus including a track battery 35 connected across one end of the section rails and a track relay TR connected across the other end of the section rails. The track relay 4TR for section 4T is shown at the end of the section adjacent section 3T, while a repeater of this relay 40 is located at the other end of the section and is designated 4TPR.

Movement of traffic along the main track from 45 left to right through the switch 3W is governed by a signal 4SA, while movement of traffic from the branch track 3PS through the switch 3W is governed by a signal 4SB. Similarly, movement 50 of traffic from right to left along the main track through the switch 5W is governed by a signal 5SA, while movement of traffic from the branch track 5PS through the switch 5W is governed by a signal 5SB.

The signals associated with the switches 3W and 5W may be of any appropriate type and are here shown as being of the searchlight type. The 55 signals 4SA and 5SA each have an upper portion

capable of displaying a proceed or a stop indication, and a lower or call-on portion capable of displaying a proceed indication. The signals 4SB and 5SB are each capable of displaying a stop indication and a proceed indication.

The signals 4SA and 4SB are governed by a signal control lever 3K, while the signals 5SA and 5SB are governed by a signal control lever 5K. The levers 3K and 5K may form portions of interlocking machines, and each of these levers may also govern other signals, not shown, for controlling traffic in the direction opposite to that controlled by the signals which are shown.

Each lever 3K and 5K has an intermediate position N in which it causes the associated signals to display their stop indications, and is movable from its intermediate position to a left-hand position L or a right-hand position R to permit the signals controlled thereby for one or the other direction of traffic to be conditioned to display proceed indications.

The signals 4SA and 4SB have associated therewith a relay 4RGP which is governed in accordance with the aspects displayed by these signals so as to be energized when and only when these signals display their stop indications, and to be deenergized if either of them displays a proceed indication. Similarly, a relay 5RGP is controlled so as to be energized when and only when the signals 5SA and 5SB display stop indications and to be deenergized when either of these signals displays a proceed indication.

The relays 4RGP and 5RGP control approach locking stick relays 4RASR and 5LASR, while these relays control directional stick relays 3WSR and 5ESR. The means for controlling the approach locking stick relays 4RASR and 5LASR is not a part of this invention and these relays may be controlled in any appropriate manner, as for example as shown in Letters Patent of the United States No. 2,093,170 granted to Ronald A. McCann on September 14, 1937.

The approach locking stick relays 4RASR and 5LASR may function in the manner well known in the art to control the associated switches to prevent movement of these switches except when it is safe for them to be moved. The means for controlling the switches, and for moving them between their two positions, is not a part of this invention and has been omitted in order to simplify the disclosure.

Each signal control lever K has associated therewith a source of direct current which may be a battery designated D with an appropriate prefix. The negative terminals C of these batteries are connected together by a common line wire 10, while as hereinafter explained, energy is at times supplied from one or the other of these batteries to a circuit including in series therewith polarized traffic locking relays WFR and EFR.

The relays WFR and EFR are preferably of a type having both neutral and polar contacts and incorporating means to prevent picking up of the neutral contacts unless the relay polar contacts respond to a change in the polarity of the energy supplied to the relay. A relay which I may employ for this purpose is shown in Letters Patent of the United States No. 1,822,496, issued September 8, 1931 to Branko Lazich, while other relays which I may employ are shown in Letters Patent of the United States No. 2,250,214, issued July 22, 1941 to Harry E. Ashworth, in application Serial No. 402,609 by Andrew Hufnagel, and in application Serial No. 424,151 by Arthur E.

Dodd, now Patent No. 2,324,200, dated July 13, 1943.

The switches 3W and 5W have associated therewith polar indication relays WPR, and means governed in accordance with the position of each switch is provided for supplying to the associated indication relay energy of normal or reverse polarity.

In most cases the contacts of each relay are shown in the drawing directly beneath the winding of the relay, but in some instances, in order to simplify the drawing, relay contacts are shown separated from the relay winding and where this is done the relay with which the contacts are associated is indicated by appropriate reference characters located directly above the contacts.

The equipment is shown in the condition which it assumes when the track stretch is vacant, the switches 3W and 5W are in their normal positions, and the signal control levers 3K and 5K are in their intermediate positions.

As the lever 3K is in its intermediate position, its contact 12 interrupts the circuits of the signals 4SA, while its contact 14 interrupts the circuit of the signal 4SB, and its contact 15 establishes a circuit for supplying energy to the approach locking stick relay 4RASR. This relay is energized at this time by current supplied over its stick circuit which includes front contact 16 of relay 4RGP and front contact 18 of relay 4RASR.

As relay 4RASR is energized, its contact 20 establishes a circuit including front contact 21 of relay 3TR for energizing the directional stick relay 3WSR, while contact 22 of this relay is picked up to establish a stick circuit to maintain the relay energized after release of contact 21 of track relay 3TR. In addition, contact 23 of the relay 3WSR is picked up to permit energy to be supplied from the battery 3D to the relays WFR and EFR.

At this time as switch 3W is assumed to be in its normal position, energy of normal polarity is supplied to the relay 3WPR by means, not shown, governed by the switch, and the neutral contact 24 of this relay is picked up, while its polar contact 25 occupies its left-hand or normal position.

As lever 5K is in its intermediate position, its contact 26 interrupts the circuits of the signals 5SA, its contact 27 interrupts the circuit of the signal 5SB, and its contact 28 establishes the circuit including front contact 30 of relay 5RGP, and front contact 31 of relay 5LASR for energizing the approach locking stick relay 5LASR. As relay 5LASR is energized, its contact 32 is picked up and establishes a circuit including front contact 34 of relay 5TR for energizing the directional stick relay 5ESR, while contact 35 of relay 5ESR is picked up to maintain the relay energized after release of the contacts of relay 5TR. As relay 5ESR is energized, its contact 36 is picked up to permit energy to be supplied from battery 5D to the relays EFR and WFR.

As the switch 5W is in its normal position, energy of normal polarity is supplied by means, not shown, to the relay 5WPR so that its neutral contact 37 is picked up and its polar contact 38 occupies its normal or left-hand position as shown.

As directional stick relay 3WSR is energized, its contact 23 is picked up and establishes connection from the positive terminal B of battery 3D through front contact 40 of relay 4TR to one terminal of the winding of traffic locking relay WFR. Similarly, as directional stick relay 5ESR is energized, its contact 36 is picked up and

establishes connection from the positive terminal B of battery 5D through front contact 41 of relay 4TPR to one terminal of the winding of traffic locking relay EFR. At this time as contact 42 of relay 4TR and contact 43 of relay 4TPR are picked up, connection is established through wire 45 between the other terminals of the windings of the traffic locking relays WFR and EFR. It follows that the relays WFR and EFR are connected in series with the batteries 3D and 5D, but that these batteries are included in the circuit in series opposition with the result that the neutral contacts of these relays are released while their polar contacts remain in their last operated positions.

Furthermore, asymmetric units 3M and 5M are included in series with the connections from the batteries 3D and 5D, respectively, and each is poled to permit energy to be supplied from its associated battery, and so to prevent supply of energy from either battery to the relays EFR and WFR if the voltage of one of the batteries should substantially exceed that of the other battery.

As neutral contact 46 of relay WFR is released, it interrupts the circuits of signals 4SA and 4SB, and as the neutral contact 41 of relay EFR is released, it interrupts the circuits of the signals 5SA and 5SB. Accordingly, as long as the traffic locking relays WFR and EFR are deenergized, the signals at both ends of the single track stretch and governing entrance of trains into this stretch are prevented from displaying proceed indications.

If it is desired to condition the apparatus to permit a train moving from left to right to enter the single track stretch, the operator controlling lever 3K may do so providing lever 5K is in its intermediate position N, or in its position R, in either of which positions it maintains the circuit of approaching locking stick relay 5LASR.

In order to condition the apparatus to permit a train moving from left to right to enter the single track stretch the lever 3K is moved to its position R, so that its contact 15 interrupts the stick circuit of approach locking stick relay 4RASR. The consequent release of contact 20 interrupts both the pick-up and stick circuits of directional stick relay 3WSR so that contact 23 of this relay releases and interrupts the connection from the left-hand terminal of the winding of relay WFR to terminal B of the battery 3D and connects this terminal of the winding of relay WFR to the common wire 10. Assuming that relay 5ESR remains energized, the relays EFR and WFR are now energized in series by current supplied from battery 5D over the circuit which is traced from terminal B of the battery 5D through asymmetric unit 5M, front contact 36 of relay 5ESR, front contact 41 of relay 4TPR, winding of relay EFR, front contact 43 of relay 4TPR, wire 45, front contact 42 of relay 4TR, winding of relay WFR, front contact 40 of relay 4TR, back contact 23 of relay 3WSR, and wire 10 to terminal C of battery 5D.

At this time, therefore, the relays WFR and EFR are energized in series by current supplied from battery 5D, and the neutral contacts of these relays are picked up while the polarity of the energy supplied to the relays is such that their contacts are moved to their right-hand or reverse positions.

Accordingly, polar contact 48 of relay EFR interrupts the circuit controlled by this relay for supplying energy to signals 5SA and 5SB and these signals are therefore prevented from displaying proceed indications.

At this time polar contact 50 of relay WFR establishes the circuit for supplying energy to one or the other of the signals 4SA or 4SB, depending on the position of the switch 3W. This switch is shown in its normal position so that energy is supplied to signal 4SA over a circuit which passes from terminal B through contacts 50 and 46 of relay WFR, contacts 24 and 25 of switch indication relay 3WPR, lever operated contact 12, and contacts 4TR and 3TR to the upper portion of signal 4SA, so that this signal gives a proceed indication. When this signal 4SA displays a proceed indication, relay 4RGP is released and its contact 16 prevents energization of the approach locking stick relay 4RASR. Accordingly, relay 4RASR remains released and prevents movement of the switch 3W, while contact 20 of relay 4RASR interrupts the circuits of the westbound directional stick relay 3WSR so that contact 23 of this relay remains released and maintains the circuit for energizing the traffic locking relays WFR and EFR from the battery 5D.

If a train accepts the proceed indication given by signal 4SA and advances into section 3T, track relay 3TR will release and its contact 21 will interrupt the pick-up circuit of relay 3WSR so that the latter relay will remain released and maintain the circuit for energizing relays WFR and EFR. In addition, when track relay 3TR releases, its contacts 17 and 19 interrupt the circuit of the upper portion of signal 4SA and the circuit of the signal 4SB so that these signals display stop indications.

When the train advances into section 4T, track relay 4TR releases and its contacts 33 and 39 additionally interrupt the circuits of the signals 4SA and 4SB, while its contact 40 additionally interrupts connection from terminal B of battery 3D to the left-hand terminal of the winding of relay WFR and connects this terminal of the relay winding to common wire 10 and thus to terminal C of battery 5D. This insures that the left-hand terminal of the winding of the traffic locking relay WFR will remain connected to terminal C of battery 5D as long as section 4T is occupied and prevents interruption of the circuit of relay WFR if the contacts of relay 3WSR should pick up after the train vacates section 3T.

In addition, on release of track relay 4TR its contact 42 interrupts the circuit for energizing relays WFR and EFR in series and establishes a stick circuit to energize the relay WFR from the battery 3D. This stick circuit is traced from terminal B of battery 3D through reverse polar contact 52 and front neutral contact 53 of relay WFR, back contact 42 of relay 4TR, winding of relay WFR, back contact 40 of relay 4TR, and common wire 10 to terminal C of battery 3D. The energy thus supplied to relay WFR from battery 3D is of the same polarity as that previously supplied to the relay from battery 5D, and maintains the relay polar contacts in their reverse positions so that polar contact 50 remains closed to permit energy to be supplied to signal 4SA or 4SB, with the result that one of these signals may display a proceed indication and thus permit a second or following eastbound train to enter the single track stretch. The energy supplied to the signal 4SA or 4SB may be supplied over the circuits controlled by track relays 3TR and 4TR, or it may be supplied over circuits established by a call-on relay 4COR. The relay 4COR may be controlled in any manner well known in the art, and its circuit is omitted from the drawing to simplify the disclosure.

As pointed out above, on release of the track relay 4TR the circuit for energizing the relays WFR and EFR in series is interrupted, and as a result the neutral contacts of relay EFR release so that contact 47 additionally interrupts the circuits of the signals 5SA and 5SB, while neutral contact 54 additionally interrupts the stick circuit for the relay EFR.

On release of relay 4TR relay 4TPR also releases and its contact 41 interrupts connection between the right-hand terminal of the winding of relay EFR and terminal B of battery 5D, while contact 43 of relay 4TPR interrupts connection from wire 45 to the left-hand terminal of the winding of relay EFR. Accordingly, relay EFR cannot be energized from either battery 3D or 5D and the neutral contacts of the relay are certain to remain released and prevent the display of a proceed indication by either signal 5SA or 5SB.

It will be seen, therefore, that after the equipment has been conditioned to permit an eastbound train to enter the single track stretch, and such a train does enter the stretch, a stick circuit is established to maintain the relay WFR energized so that it maintains the circuit to permit energy to be supplied to the signal 4SA or 4SB, while the circuit of the relay EFR is interrupted and cannot be established. This insures that the relay EFR will remain released and will prevent the display of a proceed indication by either signal 5SA or 5SB. Accordingly, after an eastbound train enters the track stretch, a second or following train may also be allowed to enter the stretch, but the equipment cannot be conditioned to cause either signal 5SA or 5SB to display a proceed indication and thus permit a westbound train to enter the single track stretch.

When the eastbound train enters section 5T, track relay 5TR releases and its contact 34 interrupts the pick-up circuit of eastbound directional stick relay 5ESR, but this relay is maintained energized by current supplied over its stick circuit which includes front contact 32 of relay 5LASR and its own front contact 35. Accordingly, contact 36 of relay 5ESR remains picked up to permit energy to be supplied from battery 5D to the relays EFR and WFR after picking up of relays 4TR and 4TPR.

Reverting to the time when the train vacates section 3T, the consequent picking up of track relay 3TR and closure of its contact 21 permits energy to be supplied over the pick-up circuit for relay 3WSR if approach locking stick relay 4RASR is picked up. The relay 4RASR will be picked up if the lever 3K has been returned to its intermediate position and the signals 4SA and 4SB display stop indications.

If relay 4RASR remains released, its contact 20 will interrupt the circuit of relay 3WSR so that contact 23 of the latter relay remains released and interrupts the supply of energy from battery 3D to relays WFR and EFR. When the train subsequently vacates section 4T so that relay 4TR picks up, the left-hand terminal of the winding of relay WFR becomes connected to the common wire 10 through front contact 40 and back contact 23.

When the track relay 4TR picks up, its contact 42 interrupts the stick circuit for relay WFR. Relay 4TPR also picks up, and the contacts 42 and 43 of relays 4TR and 4TPR respectively establish the circuit traced hereinbefore for energizing the relays WFR and EFR in series from the battery 5D. The neutral contacts of these

latter relays will be picked up and the polar contact 50 of relay WFR will establish at that point the circuit for energizing signal 4SA or 4SB, and the polar contact 52 will close so that the stick circuit for relay WFR will be completed on subsequent release of the contacts of the relay 4TR. The polar contacts of relay EFR interrupt the circuits of signals 5SA and 5SB, and also interrupt the stick circuit for the relay. Under these conditions, therefore, the apparatus is conditioned to permit another eastbound train to enter the single track stretch.

If at the time the train vacates section 3T and track relay 3TR picks up the approach locking stick relay 4RASR picks up, the pick-up circuit for the relay 3WSR will be complete and the contacts of this relay will pick up. Contact 23 of the relay 3WSR will then interrupt the connection controlled thereby from common wire 10 to the left-hand terminal of the winding of relay WFR and will connect terminal B of battery 3D to this relay after picking up of relay 4TR. As long as relay 4TR remains released, the relay WFR is energized by current supplied over its stick circuit. When the track relay 4TR picks up, relay 4TPR also picks up and the relays WFR and EFR are connected in series between the positive terminals of the batteries 3D and 5D with the result that no energy is supplied from either of these batteries to the relays WFR and EFR and the neutral contacts of these relays are released while their polar contacts remain in the positions which they last occupied. As the neutral contacts of the relays WFR and EFR are released, the circuits of the signals 3SA and 3SB, and of signals 5SA and 5SB, are interrupted, so that all of these signals are at stop.

The equipment operates in a similar manner on movement of a westbound train through the track stretch. In order to clear the signal 5SA or 5SB to permit a westbound train to enter the single track stretch the lever 5K is moved to its position L in which position contact 28 interrupts the circuit of the approach locking stick relay 5LASR so that the contacts of this relay release and interrupt the circuit of the relay 5ESR. Contact 36 of the latter relay then interrupts the path from the battery 5D to the relays WFR and EFR, and connects the right-hand terminal of the winding of relay EFR to common wire 10 so that the relays WFR and EFR are energized in series from the battery 3D. The polarity of this energy is such that the polar contacts of the relays WFR and EFR swing to their left-hand or normal positions, while the neutral contacts of these relays are picked up.

Accordingly, the contacts of relay EFR establish a circuit to permit energy to be supplied to signal 5SA or signal 5SB so that a westbound train may be authorized to enter the single track stretch, while the contacts of relay EFR also are prepared to establish a stick circuit to energize this relay from the battery 5D after the train enters section 4T and causes release of relays 4TR and 4TPR. As the polar contacts of relay WFR are in their left-hand or normal positions, the stick circuit for this relay is not established on release of relay 4TR, and the circuits for supplying energy to signals 4SA and 4SB are interrupted so that these signals display stop indications and cannot be caused to display proceed indications.

The subsequent operation of the equipment during movement of the westbound train through the track stretch will be readily understood from

the foregoing explanation of the operation during movement of an eastbound train, and need not be traced further herein.

From the foregoing it will be seen that the equipment is arranged so that the signals governing entrance of trains into the single track stretch at either end can be cleared only if the signals at the other end are displaying their stop indications. In order to clear a signal governing entrance of trains into either end of the single track stretch the traffic locking relay at that end of the stretch must first be energized with current of the polarity which is supplied from the battery at the other end of the single track stretch, and this can be done only if the directional stick relay at such other end of the stretch is picked up; the directional stick relay at either end of the stretch can be picked up when and only when the signals governing entrance of trains into that end of the single track stretch are displaying their stop indications.

Furthermore, it will be seen that as soon as a train accepts the proceed indication displayed by the signal at either end of the single track, the directional stick relay at that end of the single track stretch is prevented from picking up so that the polarity of the energy supplied to the traffic locking relays cannot be changed. This prevents clearing of the signals governing entrance of trains moving in the other direction into the single track stretch at the other end. In addition, when a train advances into the single track stretch, the circuit for energizing the traffic locking relays in series is interrupted so that the relay at the exit end of the stretch (with reference to such train) is certain to remain released and thus prevent clearing of the signal controlled thereby, but a stick circuit is established to maintain the traffic locking relay at the entrance end of the single track stretch (with reference to such train) energized with current of the same polarity as that previously supplied to the relay so that this relay permits the signals controlled thereby to be conditioned to give proceed indications and thus permit a following train to be directed into the single track stretch.

When the track stretch becomes vacated, the stick circuit for the traffic locking relay at the end of the single track stretch at which the last train entered the stretch is interrupted while the equipment is conditioned to permit the traffic locking relays to be energized in series from the battery at either end so that trains moving in either direction may be directed through the track stretch.

Although I have herein shown and described only one form of traffic locking circuit embodying my invention, it is understood that various changes and modifications may be made therein within the scope of the appended claims without departing from the spirit and scope of my invention.

Having thus described my invention, what I claim is:

1. In combination, a stretch of railway track extending between a first and a second location and over which traffic may move in either direction between said two locations, a first signal at the first location governing entrance of trains into said track stretch, a second signal at the second location governing entrance of trains into said track stretch, a first polarized relay at the first location, means effective when and only when said first polarized relay is energized by current of normal polarity to permit said first signal to provide a proceed indication, a second polarized relay at the second location, means effective when and only when said second polarized relay is energized by current of reverse polarity to permit said second signal to provide a proceed indication, a line circuit over which said polarized relays may be energized in series, means including a contact closed only when said first signal is to be cleared for energizing said polar relays in series with current of normal polarity supplied over said line circuit provided said track stretch is vacant and said second signal is displaying its stop indication to thereby permit the first signal to provide a proceed indication and prevent the display of a proceed indication by the second signal, means including a contact closed only when said second signal is to be cleared for energizing said polar relays in series with current of reverse polarity supplied over said line circuit provided said track stretch is vacant and said first signal is displaying its stop indication to thereby permit the second signal to provide a proceed indication and prevent the display of a proceed indication by the first signal, and means effective when a train enters said track stretch to interrupt said line circuit and to establish a stick circuit to supply to the polarized relay associated with the signal permitted to display a proceed indication energy of the same polarity that was supplied to said relay over said line circuit to thereby cause said relay to maintain the established direction of traffic until said track stretch is vacated.
2. In combination, a stretch of railway track extending between a first and a second location and over which traffic may move in either direction between said two locations, a first signal at the first location governing entrance of trains into said track stretch, a second signal at the second location governing entrance of trains into said track stretch, a first polarized relay at said first location, means effective when and only when said first polarized relay is energized by current of normal polarity to permit said first signal to provide a proceed indication, a second polarized relay at said second location, means effective when and only when said second polarized relay is energized by current of reverse polarity to permit said second signal to provide a proceed indication, a first source of direct current at the first location, a second source of direct current at the second location, a line circuit extending between said first and second locations, means including a contact closed only when said first signal is to be cleared for energizing said polar relays in series over said line circuit by energy of normal polarity from said second source provided said second signal is displaying its stop indication to thereby maintain the display of the stop indication by said second signal and permit the display of a proceed indication by said first signal, means including a contact closed only when said second signal is to be cleared for energizing said polar relays in series over said line circuit by energy of reverse polarity from said first source provided said first signal is displaying its stop indication to thereby maintain the display of the stop indication by said first signal and permit the display of a proceed indication by said second signal, and means effective when a train enters the track stretch to interrupt said line circuit and to establish a circuit to supply energy from said first source to said first polarized relay provided the contacts of said first polarized relay are in their normal positions and

to establish a circuit to supply energy of reverse polarity from said second source to said second polarized relay provided the contacts of said second polarized relay are in their reverse positions.

3. In combination, a stretch of railway track extending between a first and a second location and over which traffic may move in either direction between said two locations, a first signal at the first location governing entrance of trains into said track stretch, a second signal at the second location governing entrance of trains into said track stretch, a first polarized relay controlling said first signal, a second polarized relay controlling said second signal, means for connecting one terminal of the winding of the first polarized relay to one terminal of the winding of the second polarized relay, a first source of direct current at the first location, a second source of direct current at the second location, each of said sources of current having a first and a second terminal, the first terminal of each of said sources being of the same relative polarity, manually controlled means at the first location for at times connecting the other terminal of the winding of the first relay to the first terminal of the first source and at other times to the second terminal of the second source, and manually controlled means at the second location for at times connecting the other terminal of the winding of the second relay to the first terminal of the second source and at other times to the second terminal of the first source.

4. In combination, a stretch of railway track extending between a first and a second location and over which traffic may move in either direction between said two locations, a first signal at the first location governing entrance of trains into said track stretch, a second signal at the second location governing entrance of trains into said track stretch, a first polarized relay controlling said first signal, a second polarized relay controlling said second signal, means for connecting one terminal of the winding of the first polarized relay to one terminal of the winding of the second polarized relay, a first source of direct current at the first location, a second source of direct current at the second location, each of said sources of current having a first and a second terminal, the first terminal of each of said sources being of the same relative polarity, manually controlled means at the first location for at times

connecting the other terminal of said first relay to the first terminal of the first source and at other times to the second terminal of the first and second sources, manually controlled means at the second location for at times connecting the other terminal of the second relay to the first terminal of the second source and at other times to the second terminal of the first and second sources, means including a contact of said first relay by which connection may be established from the first terminal of said first source to said one terminal of said first relay when said track stretch is occupied, and means including a contact of said second relay by which connection may be established from the first terminal of said second source to said one terminal of said second relay when said track stretch is occupied.

5. In combination, a stretch of railway track extending between a first and a second location and over which traffic may move in either direction between said two locations, a first signal at the first location governing entrance of trains into said track stretch, a second signal at the second location governing entrance of trains into said track stretch, a first polarized relay controlling said first signal, a second polarized relay controlling said second signal, means for connecting one terminal of the winding of the first polarized relay to one terminal of the winding of the second polarized relay, a first source of direct current at the first location, a second source of direct current at the second location, each of said sources of current having a first and a second terminal, the first terminal of each of said sources being of the same relative polarity, manually controlled means at the first location for at times connecting the other terminal of the winding of the first relay to the first terminal of the first source in series with a first asymmetric unit and at other times to the second terminal of the second source, and manually controlled means at the second location for at times connecting the other terminal of the winding of the second relay to the first terminal of the second source in series with a second asymmetric unit and at other times to the second terminal of the first source, each of said asymmetric units being arranged to permit energy to be supplied from the associated source of current to said relays and to prevent the supply of energy from the other source of current to said relays over a circuit including said unit in series therewith.
